UNITED STATES PATENT OFFICE

2,574,792

GRAIN CONVEYER AND ELEVATOR

David Love, Edmonton, Alberta, Canada

Application July 12, 1949, Serial No. 104,247
In Canada July 19, 1948

2 Claims. (Cl. 214—83:26)

1

This invention relates to improvements in grain conveyors and elevators and embodies features and improvements to my two previous Canadian Patents Numbers 394,917 and 412,525.

Broadly the invention comprises a tube adjustable vertically and horizontally, a feed screw rotatable in the tube, a train of gears to operate the feed screw and a power take off to operate the train gear. Associated with the tube is a manual means of elevating or lowering said tube.

The principal object of the invention is to provide a more efficient mechanical means of adapting the power of the vehicle's motor to operate the loader and this whether the vehicle be in operation or in a stationary position.

A further object is to provide a conveyor of the character set forth which may load grain from a position below or above the vehicle level.

A still further object is to provide operating means associated with said conveyor whereby the vehicle power may be used to drive said means.

A still further object is to provide a horizontally and vertically adjustable conveyor as set forth which may be operated during the change of position.

With these and other objects in view that may appear while the description proceeds the invention consists in the novel arrangement of cooperating parts as hereinafter more specifically set forth, claimed and shown in the accompanying drawings forming part of this application and in which:

Fig. 1 is a side elevational view of a truck showing the conveyor mounted thereon;

Fig. 2 is a plan view of the truck box showing how the driving means is transmitted from the power take-off to the conveyor driving means;

Fig. 3 represents a side elevational view of the drive assembly;

Fig. 4 is a sectional view through Figure 3;

Fig. 5 is a detail of the tube construction showing the bevel gears attached thereto;

Fig. 6 is a side view of Fig. 5;

Fig. 7 shows an enlarged detail of the extremity of the conveyor tube and the manner in which the conveyor is mounted.

Referring more in detail to the drawings in which similar reference characters designate corresponding parts throughout the several views, it will be seen the invention consists of a truck 10 having an open top body 11 which is used to transport grain or like material and on which my invention is mounted.

In carrying out the invention a telescopically adjustable tubular member 12 is secured to an

interior wall of the body and projects above the top thereof and it also extends through the bottom of the body where it is coupled to a gear housing 13 mounted beneath the floor and secured thereto by means of bolts 14 or the like.

In the housing 13 are disposed a pair of bevel gears 14a in meshing engagement, the horizontally disposed gear being coupled directly to the main drive shaft 15 disposed within the tubular member 12. The other gear is secured to a horizontally disposed secondary shaft 16 which is journaled in the housing 13 and to one extremity of which is coupled a universal joint 17. To the universal joint 17 is secured a rod 18 and with the aid of further rods and universal joints are directly connected to a power take off 19, said power take off being coupled to the vehicle transmission. The main drive shaft assembly Figs. 3 and 4, comprises a tubular drive shaft 15 at the upper extremity of which is telescopically mounted a secondary shaft 20 having its lower portion 21 square while the upper portion 22 is round. When the device is extended upwardly the square portion of the shaft 21 slides in grooves in tubular shaft 15 and both shafts remain in constant engagement. The outer tube 23 being coupled to shaft 22 follows same in an upward position and assures at all times that rotating parts are not easily accessible thus eliminating danger of serious accidents to operators. The upper extremity of the tubular shaft 15 rotates within a brass bushing 24 which is held to a tube 25 disposed within outer tube 23. The lower extremity of said shaft 15 is also journaled in a similar brass bushing 24a.

To raise or lower the tube manually the following mechanism is used. A collar 26 is fastened to the upper extremity of the tube 23.

The said collar is Z shaped and due to its particular shape it extends over the side wall of the truck body. A rack 27 depends therefrom. A bracket 28 is secured to said side wall and a worm 29 is rotatably mounted in said bracket and engages rack 27. A crank 30 is provided to manually operate the worm 29 which will cause the driving elements to raise or lower in accordance with the direction of rotation of said worm. The rack 27 is secured to the collar extension 31 by means of bolts 32 and slides between guides 33 of the bracket 28.

The conveyor, per se is mounted in a cradle 34 and comprises a cradle supporting bracket 35 pivotally secured to the cradle at 36 and through which extends the driving shaft 22. At the upper extremity of the said driving shaft 22 and

within the cradle bracket is secured a bevel gear 37 which is in meshing engagement with a combination spur and bevel gear 38. The shaft supporting gear 38 is the pivoting point 36 between the cradle 34 and the cradle bracket 35. The power to rotate the conveyor feed screw 39 is transmitted from gear 38 to a similar gear 40 then to a common bevel gear 41. The gear 41 is supported on a square shaft 42 and is mounted in the cradle 34 by means of a bearing frame 43.

Slidably mounted in the cradle is the conveyor tube 44. It is disposed in a ring 45 in which a projection 46 is formed to receive a guide rod 47. This guide rod will prevent any twisting of the tube 44 and will assure that it constantly travels in a direct line. At one extremity of the tube is a discharge spout 48 while at the other is a frame 49 carrying a bushing 50 for the feed screw 39. The said frame is mounted on the tube by means of straps 51 secured therearound and held fast by means of bolts 52.

The feed screw is operated by means of a chain and sprocket drive. The square shaft 42 is rotated through the medium of the aforescribed train of gears which are operated by the drive shaft 22 and in turn operates a sprocket 53 which is coupled to its extremity beyond a supporting bracket 54. A sprocket 55 is also coupled to the feed screw and both sprockets are joined by a chain 56. At its other extremity, the square shaft 42 is supported by a bushing 57 supported to the tube by means of a strap 58.

The cradle 34 will permit horizontal adjustment of the tube while said tube is rotatable and adjustable in any direction since its supporting bracket 35 is mounted on a round shaft. Since the tube is adjustable in any position and that it may be raised or lowered it will readily be understood that the pick up extremity may be set at a point higher or lower than the truck body on which it is mounted and load grain from any position.

It is believed that the construction and advantages of the invention may be apparent from the foregoing paragraphs taken in conjunction with the accompanying drawings without further detailed description.

While the preferred embodiment of the invention has been disclosed it is understood that minor changes in the details of construction, combination and arrangement of co-operating parts may be resorted to within the scope of what is claimed without departing from the spirit of the invention.

I claim:

1. A loading conveyor for motor trucks comprising a vertical telescopic shaft mounted parallel to the side wall of the truck body, a conveyor tube rotatable and rockably mounted on the upper end of said drive shaft, a screw conveyor rotatable in said tube having driving connection with said drive shaft, a casing encasing said drive shaft having connection with the upper section of said drive shaft, an extension projecting laterally from said casing beyond the side wall of the truck body, a rack bar attached to and depending from said extension, a bracket attached to the side wall of the truck body, and a worm journaled in said bracket in mesh with said rack bar adapted upon rotation to move said rack bar to raise and lower the upper section of said drive shaft to adjust the horizontal position of said conveyor tube.

2. A loading conveyor for motor trucks comprising a vertical telescopic drive shaft mounted parallel to the side wall of the truck body with the lower end of the lower section extending through the bottom of the truck body, a horizontal conveyor tube pivotally mounted above the upper end of said drive shaft, a screw conveyor rotatably mounted in said tube, gearing connecting said drive shaft with said screw conveyor, a tubular casing encasing said drive shaft, a collar attached to said casing having a lateral extension extending over the side wall of the truck body, a rack bar attached to the extension of said collar and depending therefrom in parallel relation to the side wall of the truck body, a bracket attached to the side wall of the truck body, and a worm journaled in said bracket in mesh with said rack bar adapted upon rotation to move said rack bar to raise and lower the upper section of said drive shaft to adjust the horizontal position of said conveyor tube.

DAVID LOVE.
